COMBINED POCKET HAIR COMB AND NAIL FILE

Guy W. Edmunds, Long Grove, Ill.
(152 Kimberly Road, East Dundee, Ill. 60118)

Filed Sept. 27, 1971, Ser. No. 184,319

Term of patent 14 years

Int. Cl. D28—03

U.S. Cl. D86—8

FIG. 1 is a front elevational view showing my new design for combined pocket hair comb and nail file;

FIG. 2 is a rear elevational view thereof;

FIG. 3 is a bottom plan view thereof;

FIG. 4 is a top plan view thereof;

FIG. 5 is an elevational view as seen from the handle end; and

FIG. 6 is an elevational view opposite that shown in FIG. 5.

I claim:

The ornamental design for a combined pocket hair comb and nail file, as shown.
